UNITED STATES PATENT OFFICE.

EDMUND C. MORGAN, OF CHICAGO, ILLINOIS, ASSIGNOR TO THE MORGAN ELECTRIC MACHINE COMPANY, OF SAME PLACE.

ELECTRIC-RAILWAY SYSTEM.

SPECIFICATION forming part of Letters Patent No. 659,178, dated October 2, 1900.

Application filed January 2, 1900. Renewed September 10, 1900. Serial No. 29,474. (No model.)

To all whom it may concern:

Be it known that I, EDMUND C. MORGAN, a citizen of the United States, residing at Chicago, in the county of Cook and State of Illinois, have invented a new and useful Electric-Railway System, of which the following is a specification.

This invention relates to electric-railway systems.

10 One object of the invention is to provide an electric-railway system wherein the truck is supported upon truck-wheels, wherein propulsion is effected through a gear and rack, the gear being driven from a motor supported by the truck.

15 Other objects of the invention will appear more fully hereinafter.

The invention consists substantially in the construction, combination, location, and arrangement of parts, all as will be more fully hereinafter set forth, as shown in the accompanying drawings, and finally pointed out in the appended claims.

20 Referring to the accompanying drawings, and to the various views and reference-signs appearing thereon, Figure 1 is a view in side elevation of a railway-truck, showing the application thereto of a construction embodying the principles of my invention. Fig. 2 is a 25 transverse central section of the same on the line 2 2 of Fig. 1. Fig. 3 is a detached detailed broken view showing means for centering the propelling sprocket or gear. Fig. 4 is a broken view in plan showing a track system, a switch, 30 and the application thereto of a third or traction rail embodying the principles of my invention. Fig. 5 is a broken detail view in plan of a form of combined third and traction rail constructed in accordance with the principles 35 40 of my invention. Fig. 6 is a transverse section of the same on the line 6 6 of Fig. 5.

The same part is designated by the same reference-sign wherever it occurs throughout the several views.

45 I will first describe the construction and arrangement of the combined third and traction rail employed in connection with my invention. Suitably mounted and secured upon the ties A of the railway-track bed are blocks 50 B, of insulating material—say, for instance, of wood. Suitably mounted upon and secured

to the blocks B are two stringers C D, arranged to extend longitudinally with respect to the track-rails E and spaced a suitable distance apart to accommodate therebetween the third 55 and traction rail. Preferably and as shown the stringers C D are correspondingly grooved or recessed longitudinally upon the juxtaposed faces or surfaces thereof and at a suitable point intermediate their edges, as 60 most clearly shown in Fig. 6. Arranged in the groove or recess in the face or side of each stringer C D is a plate F G. These plates are connected together at suitable intervals by means of bolts H, said bolts alternately passing through said plates in opposite directions and secured in the stringers C D, respectively, as clearly shown. Intermediate the plates F G each bolt carries or has otherwise secured thereon a sleeve J. The suitably-spaced bolts 70 H and the side plates or bars F G, which they connect, constitute an open rack. The said bolts or sleeves J, carried or formed thereon, constitute the teeth of such rack and adapted to be engaged by the teeth of a suitable propelling gear or sprocket carried by the truck whereby said truck is propelled along the track. By this construction of the traction-rack and the manner of supporting the same it will be seen that such rack is efficiently insulated and may therefore form a conductor 75 by which current is supplied to the motor on the truck which operates the propelling gear or sprocket, thus avoiding the use of an independent trolley wire or conductor for supplying such current. It will also be seen by the arrangement above described that such combined third or traction rail is located between the edges of the stringers C D, and hence out of danger of accidental contact therewith, thus 80 affording protection to pedestrians or others. If desired and in order to form a traction-rack of sufficient length, such rack may be made in sections, the sections bolted together at the ends, as indicated at K, Fig. 5. By arranging the side bars F G of the combined third and traction rail within grooves or recesses formed in the stringers C D such rail is efficiently held supported and braced to resist the strains exerted thereon by the propelling 85 power.

A combined third and traction rail con-

structed in accordance with the principles above set forth may be arranged in any suitable or convenient relation with respect to the traction-rails. In practice, however, I 5 prefer to arrange such third or traction rail between the track-rails E, as clearly shown in Fig. 2, and preferably in closer relation to one rail than to the other, as clearly shown, thus affording an ample space for foot-passage, 10 when necessary or desired, between the track-rails.

I will now describe the construction and arrangement of the truck and the propelling devices mounted or carried thereon. Reference-sign L designates a motor, which may be of any suitable or convenient type, construction, and arrangement, the shaft of which is suitably journaled in the truck-frame M. In 15 practice I prefer to employ an electric motor, and I have found a shunt-wound constant-speed electric motor efficient for the purpose. Suitably journaled in the truck-frame is a shaft N, adapted to be driven from the motor in any suitable manner. I have shown a suitable 20 arrangement of gearing for driving shaft N from the motor at different speeds and comprising gears O P of different sizes, which gears are loosely sleeved upon said shaft N. The gears O and P are constantly driven from 25 the motor-shaft by the engagement therewith of corresponding driving-gears Q R', also differing in size to correspond to the difference in relative size of gears O and P. Suitably connected to rotate with shaft N are friction-gears R S, arranged to be alternately engaged 30 with gears O P, respectively. Thus when friction-gear R is engaged with gear O the shaft N is driven at one speed and the friction-gear S is disengaged from gear P, and 35 when said friction-gear S is shifted to engage gear P the shaft N is driven in the same direction as before, but at a different speed, depending upon the difference in relative sizes of gears O P and their driving-gears Q R', the movement of friction-gear S to engage 40 gear P effecting a disengagement of the friction-gear R with gear O. The shifting of friction-gears R S may be effected in any suitable or convenient manner—as, for instance, 45 by means of a hand-lever T, suitably connected by connecting-links or otherwise with the hubs of said friction-gears.

Suitably bolted or otherwise mounted on or secured to the sills W of the truck-frame are 50 castings or brackets 8 9, in which are suitably held shafts 10 11 12. Loosely sleeved upon shaft 10 is a gear-wheel 13, arranged to be driven from shaft N through the engagement therewith of a gear 14, mounted on said 55 shaft N, and said gear 13 intermeshes with and drives gears 15 and 16, (see Fig. 1,) respectively mounted on shafts 11 12. Suitably connected to revolve with the gears 11 12 is a sprocket or propelling gear 17 18, said 60 sprocket or propelling gears being arranged to operate in substantially the same vertical plane and to engage or intermesh with the

teeth of the combined third or traction rail. In practice I prefer to hold the shafts 10, 11, and 12 stationary and to arrange the gears 70 13, 15, and 16 to revolve freely on said shafts respectively. By this construction I avoid the necessity of cutting feathers or grooves in said shafts or the hubs of said gears and at the same time produce an easy and smooth 75 running gearing.

The truck-wheels 20 21 are arranged in pairs at each end of the truck-frame, said truck-wheels being supported upon pins or studs 22, suitably bolted or otherwise secured to 80 the truck-frame. Thus the truck-wheels operate merely as supporting-wheels for the truck, the propulsion being effected through the engagement of the propelling or sprocket gears 17 18 with the traction-rail, as above described. In practice I prefer to arrange a propelling or sprocket gear 17 18 adjacent to each pair of truck-wheels 20 21 for a purpose presently to be described. By loosely 85 sleeving the gears 15 16 and their connecting propelling or sprocket gears 17 18 upon their respective supporting-shafts 11 12 said gears and their connected propelling-sprockets are permitted a desirable range of lateral movement transversely with respect to the truck-frame. This is a desirable feature, for the reason that the propelling or sprocket gears enter the space between the stringers C D of the traction-rail in order to effect engagement with such traction-rail, and hence any 90 lateral motion or vibration of the truck or lateral movement thereof in turning curves or the like will be permitted by the lateral movement of the propelling or traction gears or sprockets without danger of unduly straining such gears or sprockets or causing the traction-rail stringers to work loose or to be deranged from the proper alignment thereof. If desired and in order to yieldingly hold the 95 sprocket-gears in centered relation with respect to the traction-rail, each of said sprockets may be engaged by a spring 23, Fig. 3.

Where the motor employed is an electric motor, the traction-rail serves also as a conductor for supplying current thereto. Such 100 current is supplied through the contact of the propelling sprocket-gears with said traction-rail, and in this event to prevent short-circuiting the gear 13 should be insulated 105 from its driving-gear 14. A convenient arrangement is shown wherein the driving-pinion 14 is insulated from shaft N, the current being conveyed from the propelling-sprockets to the motor in any suitable manner, as by wire 24, the return circuit being completed, as indicated, through wire 25 (see Fig. 1) to one or more of the truck-supporting 110 wheels 20 21, said wheels being suitably insulated from the truck-frame.

In Fig. 4 I have shown an arrangement of 115 tracks and a switch or crossing adapted for use in connection with my invention. In such arrangement the traction-rail must be made in disconnected sections in order to

accommodate in the usual manner the track-rails, and by the arrangement of the propelling-sprockets, as above described, at each end of the truck-frame and the gaps 5 between adjacent sections of the traction-rail bearing a definite proportion to the diameter and speed of rotation of the propelling-gears it will be seen that the gaps in the traction-rail may be readily and easily jumped 10 over or passed, the one propelling-gear at the front end of the truck, for instance, engaging the advance section of the traction-rail before the other propelling-gear at the rear end of the truck leaves the rear section of 15 the traction-rail. In this manner and by operating the propelling-gears synchronously an engagement between one or the other of the propelling-sprockets and one or another of the sections of the traction-rail is 20 constantly maintained.

Having now set forth the object and nature of my invention, what I claim as new and useful and of my own invention, and desire to secure by Letters Patent of the United States, 25 is—

1. In an electric-railway system, track-rails, a truck, supporting-wheels therefor arranged to operate on said rails, a traction-rack arranged parallel with said track-rails, supporting-stringers for said rack, said rack arranged between said stringers and intermediate the edges thereof, a propelling-gear mounted on said truck, and arranged to enter the space between said stringers to engage 30 said rack and the motor carried by said truck for operating said propelling-gear, as and for the purpose set forth.

2. In an electric-railway system, track-rails, a truck, supporting-wheels therefor arranged 40 to operate on said track-rails, a traction-rack arranged parallel with respect to said track-rails, supporting-stringers for said rack, said rack arranged between said stringers and intermediate the edges thereof, a propelling-gear mounted on said truck for lateral movement with respect thereto and arranged to enter the space between said stringers to engage 45 said rack, and a motor carried by said truck for operating said gear, as and for the purpose set forth.

3. In an electric-railway system, track-rails, a truck, supporting-wheels therefor arranged to operate on said track-rails, a traction-rack, a propelling-gear mounted on said truck for lateral movement with respect to said truck and arranged to engage said rack and a motor carried by said truck, and arranged to operate 55 said gear, as and for the purpose set forth.

4. In an electric-railway system, track-rails, 60 a truck, supporting-wheels therefor arranged to operate on said track, a traction-rack arranged parallel with respect to said rails, a propelling-gear carried by said truck and arranged to engage said rack, said gear mounted 65 for lateral movement with respect to said truck, and means for yieldingly holding said gear in centered relation with respect to said

rack in combination with a motor carried by said truck for operating said gear, as and for the purpose set forth.

5. In an electric-railway system, track-rails, a truck, supporting-wheels therefor operating on said rails, a traction-rack arranged in parallel relation to said rails, supporting-stringers for said rack, said rack arranged between 75 said stringers and intermediate the edges thereof, a propelling-gear mounted on said truck and arranged to enter the space between said stringers to engage said rack, said gear mounted for lateral movement with respect to said truck, means for yieldingly holding 80 said gear in centered relation with respect to said rack in combination with a motor carried by said truck for operating said gear, as and for the purpose set forth.

6. In an electric-railway system, track-rails, a truck supported thereon, a traction-rack, a propelling-gear carried by said truck and arranged to engage said rack, springs arranged to engage said gear to yieldingly hold the 90 same in centered relation with respect to said rack, and a motor carried by said truck for operating said gear, as and for the purpose set forth.

7. In an electric-railway system, a truck, 95 track-rails upon which said truck is supported, a traction-rack, a fixed shaft mounted on said truck, a propelling-gear loosely sleeved upon said shaft, a motor carried by said truck and gearing intermediate said motor and propelling-gear for actuating the latter, as and for the purpose set forth.

8. In an electric-railway system, a truck, track-rails, upon which said truck is supported, brackets or castings mounted on said 105 truck, a shaft stationarily supported by said brackets or castings, a propelling-gear loosely sleeved upon said shaft, an intermediate shaft also mounted in said brackets or castings, a driving-gear mounted thereon, and arranged to engage and drive said propelling-gear, a motor carried by the truck and arranged to drive said driving-gear in combination with a traction-rack arranged to be engaged by said propelling-gear, as and for the 110 purpose set forth.

9. In an electric-railway system, a truck, track-rails upon which said truck is supported, and a traction-rack in combination with a propelling-gear carried by said truck 120 and arranged to engage said rack, a drive-shaft for said propelling-gear, drive-gears of different sizes loosely mounted on said drive-shaft, a motor having gears of corresponding difference in size arranged to engage and actuate said drive-gears, a friction-gearing arranged to be alternately shifted to engage and disengage said driving-gears from said drive-shaft, as and for the purpose set forth.

10. In an electric-railway system, a truck, 130 track-rails upon which said truck is supported and a traction-rack in combination with propelling-gears mounted on said truck at the respective ends thereof and arranged

to engage said rack, in combination with a motor carried by said truck, and gearing actuated by said motor for synchronously operating said propelling-gears, as and for the 5 purpose set forth.

11. In an electric-railway system, a truck, track-rails upon which said truck is supported, and a traction-rack in combination with a fixed shaft mounted at each end of 10 said truck, a propelling-gear loosely sleeved upon each fixed shaft, a motor carried by said truck and gearing intermediate said motor and propelling-gears for actuating the latter, as and for the purpose set forth.

15 12. In an electric-railway system, a com-

bined traction and third rail comprising stringers having seats or grooves in the juxtaposed faces thereof, and intermediate their edges, plates arranged in said grooves or seats, and bolts passing through said plates 20 to form rack-teeth, as and for the purpose set forth.

In witness whereof I have hereunto set my hand this 29th day of December, 1899, in the presence of the subscribing witnesses.

EDMUND C. MORGAN.
